UNITED STATES PATENT OFFICE.

WAYLAND J. COPP, OF CHICAGO, ILLINOIS.

SPOON-CLIP.

1,323,838.

Specification of Letters Patent. Patented Dec. 2, 1919.

Application filed January 24, 1917. Serial No. 144,214.

To all whom it may concern:

Be it known that I, WAYLAND J. COPP, a citizen of the United States, residing at Chicago, in the county of Cook and State 5 of Illinois, have invented certain new and useful Improvements in Spoon-Clips, of which the following is a specification.

This invention relates to one piece metal clip to be attached to a table utensil such 10 as a spoon or the like, to keep the handle from sliding into a dish, in which the spoon is placed, such instances being of frequent occurrence when dishes are passed around the table and being very annoying.

15 In the drawings:—

Figure 1 is a perspective view of the invention shown as applied to a spoon in use.

Fig. 2 is a perspective view of the clip.

Fig. 3 is a perspective view showing the 20 method of manufacturing the clip.

Fig. 4 is a transverse vertical cross section through the clip.

The clip of my invention is made from a flat blank of the shape shown in full lines 25 in Fig. 3, and comprising a broad portion 1, having extensions 2 and 3 thereon. The blank should consist of metal of substantial thickness such as steel, which may be silver plated, or may be made of silver if desired, 30 sufficient thickness being left at the base of the projection 2 to afford the necessary stiffness and resiliency in action. The part 2 is bent over as indicated in Fig. 2, and the projection 3 bent downwardly, after which the 35 corners may be bent up as indicated at 4.

The completed device will then be ready to be slipped sidewise over a spoon. It will, on account of its resiliency and stiffness, firmly clamp the spoon and prevent the 40 same from falling into a dish or the like.

It is particularly to be noted that the clamp may be placed in any position on the spoon, the projection 3 working just as well from one side as from the other.

Though this description refers to the device described primarily in connection with spoons, it will of course be understood that it is also adapted for use with other table silver.

Having now described my invention, I 50 claim:

An attachment for spoons, forks and the like comprising a clip formed from a single piece of flat L-shaped material and having a body portion, a resilient arm formed by 55 bending one arm of said L-shaped portion back upon, approximately parallel with and sufficiently spaced from said body portion to form a slot of approximately the thickness of a spoon handle, whereby to form 60 resilient jaws so that said clip may be quickly and securely attached to a spoon or the like by inserting the same between said parallel resilient arm and body portion, and an integral angularly extending 65 projection on said body portion formed by bending downwardly the other arm of said L-shaped portion into a position to form a substantial projection to engage the edge 70 of a dish and prevent the spoon to which said clip is secured from sliding down into the contents of the dish.

In witness whereof, I hereunto subscribe my name to this specification in the presence of two witnesses.

WAYLAND J. COPP.

Witnesses:

SEBASTIAN HINTON,
C. I. SHERMAN.

It is hereby certified that in Letters Patent No. 1,323,838, granted December 2, 1919, upon the application of Wayland J. Copp, of Chicago, Illinois, for an improvement in "Spoon-Clips," an error appears in the printed specification requiring correction as follows: Line 67, claim, strike out the word "downwardly"; and that the said Letters Patent should be read with this correction therein that the same may conform to the record of the case in the Patent Office.

Signed and sealed this 13th day of January, A. D., 1920.

[SEAL.]

M. H. COULSTON,
Acting Commissioner of Patents.

Cl. 65—65.
